CLAIM

The ornamental design for a filter holder, as shown and described.

DESCRIPTION

FIG. 1 is a first perspective view of the filter holder of the present invention.

FIG. 2 is a front view of the filter holder of the present invention.

FIG. 3 is a rear view of the filter holder of the present invention.

FIG. 4 is a left-side view of the filter holder of the present invention.

FIG. 5 is a right-side view of the filter holder of the present invention.

FIG. 6 is a top view of the filter holder of the present invention; and,

FIG. 7 is a bottom view of the filter holder of the present invention.
